(57) **CLAIM**

We claim the ornamental design for an golf club head, as shown and described.

DESCRIPTION

FIG. 1 is a perspective view of a golf club head, as viewed from the toe and front sides, according to an embodiment of the design.

FIG. 2 is a front elevation view of the golf club head of FIG. 1.

FIG. 3 is a rear elevation view of the golf club head of FIG. 1. FIG. 4 is a side elevation view from a toe side of the golf club head of FIG. 1.

FIG. 5 is a side elevation view from an opposite heel side of the golf club head of FIG. 1.

FIG. 6 is a top plan view of the golf club head of FIG. 1.

FIG. 7 is a bottom plan view of the golf club head of FIG. 1. FIG. 8 is a front elevation view of a golf club head, according to a second embodiment of the design; and,

FIG. 9 is a front elevation view of a golf club head, according to a third embodiment of the design.

The dashed lines in the drawings are for purposes of illustrating environmental structure as well as portions of the design that form no part of the claimed design.
